Attorney, Agent, or Firm—Jack L. Oney, Jr.; Leonard W. Lewis

[57] **CLAIM**

The ornamental design for a bottle, as shown and described.

DESCRIPTION

FIG. 1 is a top, front and right side perspective view of a bottle showing our new design;

FIG. 2 is a top view thereof;

FIG. 3 is a front elevational view thereof; the rear elevational view thereof being identical;

FIG. 4 is a left side elevation thereof; and,

FIG. 5 is a bottom view thereof.

The broken lines showing the bottle cap in the drawings are for illustrative purposes only and do not part of the claimed design.
